UNITED STATES PATENT OFFICE.

JOHN W. TILLEY, OF WHITES CREEK, WEST VIRGINIA, ASSIGNOR OF ONE-HALF TO
THOMAS J. FLETCHER, OF WHITES CREEK, WEST VIRGINIA.

FLOOR-SURFACING MACHINE.

Application filed July 27, 1927. Serial No. 208,819.

This invention relates to a floor surfacing machine, the general object of the invention being to provide a wheeled frame having a vertically movable supporting frame thereon which carries a plurality of reciprocating shoes which carry the sandpaper or other abrasive material, with power means on the first frame for reciprocating the shoes.

A further object of the invention is to provide hand operated means for raising and lowering the shoe carrying frame and also to provide a suction device driven by the power means for removing the sand and other material from the floor in rear of the shoes.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a top plan view of the machine.

Figure 2 is a side view thereof.

Figure 3 is a longitudinal sectional view.

Figure 4 is a section on line 4—4 of Figure 3.

Figure 5 is a section on line 5—5 of Figure 1.

Figure 6 is a section on line 6—6 of Figure 3.

Figure 7 is a section on line 7—7 of Figure 1.

Figure 8 is a section on line 8—8 of Figure 2.

Figure 9 is a section on line 9—9 of Figure 2.

In these views 1 indicates a casing-like body which is supported by the side wheels 2 and the caster wheel 3 and which is adapted to be pushed along a floor by the handle 4 which is attached to the rear of the body above the caster wheel. A frame 5 is supported for vertical movement at the front of the body by having the ribs 6 on the rear side of the frame engaging the guideways 7 in the front of the body, the frame being movable by means of the lever 8 pivoted to the upright 9 attached to the front of the body, the lever being connected at its front end to a cross rod 10 which is connected with the sides of the frame by the members 11. Thus by press-

ing down upon the rear end of the lever which is arranged adjacent the handle 4, the frame can be raised. I provide a screw shaft 12 for holding the lever in adjusted position, this shaft passing through a threaded opening in a bracket 13 attached to the rear part of the body and said shaft has a spherical end 14 engaging a socket in a member 15 which is pivoted in an opening 16 formed in the rear end of the lever 8.

The frame 5 is provided with a number of groups of horizontal guide bars 17, there being four guide bars to a group, these guide bars being parallel to each other and to the sides of the frame and having their ends suitably connected with the front and rear sides of the frame. A cross head 18 is slidably arranged for horizontal movement in each group of guide bars and the stem 19 of a shoe 20 passes through each cross head so that the shoe is caused to move with the cross head.

As shown in the figures, I prefer to use four shoes, with the outer shoes of greater width than the inner shoes. Each shoe is provided with a sheet 21 of sandpaper or the like. Each sheet is removably held on the shoe by the pair of eccentric rollers 22, one arranged adjacent each end of the shoe, the trunnions of the rollers being journaled in the upstanding ears 23 fastened to the sides of the shoe.

A crank shaft 24 is journaled in the body adjacent the front thereof and connecting rods 25 connect the cranks of the shaft with the upper ends of the stems of the shoes so that the rotary moment of the crank shaft will impart a reciprocating motion to the shoes, and I prefer to so arrange the cranks that two of the shoes will be moving rearwardly while the other two will be moving forwardly. I also prefer to connect each stem with its connecting rod by means of a pin 26 which passes through the rod and the stem and has a collar 27 at its center which spaces the rod from the stem.

A motor 28 is fastened to the top of the body and its shaft carries a sprocket 29 over which passes an endless chain 30 which also passes over a sprocket 31 on one end of the crank shaft 24. A fan casing 32 is arranged in the body and the fan 33 therein is driven from the motor through means of the belt 34 and the pulleys 35, one pulley being arranged on the fan shaft and the other on the motor

shaft. The intake 36 of the fan casing is provided with a wide mouth which terminates adjacent the rear ends of the shoes when the shoes are in their rearward position so that 5 the sand from the shoes and the dirt from the floor will be drawn into the fan casing through this inlet and thus the floor will be kept clean. The exhaust pipe 37 of the fan casing passes through the top of the body 10 where it is provided with an elbow 38 to which is fastened a bag 39 by the clamping ring 40 so that this bag catches the dirt picked up by the suction means.

From the foregoing it will be seen that as 15 the machine is pushed along a floor with the motor in operation, the shoes will be reciprocated so that the sandpaper on the shoes will act on the floor and thus surface the same. The sand and material removed from the 20 floor will be picked up by the suction means and deposited in the bag 39. With this machine, a floor can be easily and quickly surfaced with but little effort on the part of the operator.

25 It is thought from the foregoing description that the advantages and novel features of my invention will be readily apparent.

I desire it to be understood that I may make changes in the construction and in the combination and arrangement of the several parts, 30 provided that such changes fall within the scope of the appended claims.

What I claim is:—

1. A machine of the class described comprising a wheeled body, having vertically arranged guideways at its front, a frame in 35 front of the body and having vertical guides

at its rear engaging the guideways at the front of the body, reciprocatory shoes carried by the frame, a crank shaft carried by the body, 40 rods connecting the cranks of the shaft with the shoes, a motor carried by the body and connected with the shaft for rotating the same, a lever pivotally connected with the body and connected with the frame for raising and lowering the frame and means for holding the lever in adjusted position.

2. A machine of the class described comprising a wheeled body, a frame connected with the front of the body, horizontal guiding means in the frame, a plurality of shoes, a stem connected with each shoe, a cross head attached to each stem, said cross heads being supported for horizontal movement in the guiding means, a crank shaft journaled in the 55 body, rods connecting the cranks thereof with the stems, a motor carried by the body and connected with the crank shaft for rotating the same, a lever pivotally supported from a part of the body and connected with the 60 frame for raising and lowering the frame, means for adjusting the lever and holding it in adjusted position and suction means within the body and operated from the motor with its inlet part extending through the bottom of 65 the body to a point in rear of the shoes for picking up the dust and dirt left by the shoes the outlet part of the suction means extending through the top of the body and a sack connected with the extremity of said outlet 70 part and arranged exteriorly of the body.

In testimony whereof I affix my signature.

JOHN W. TILLEY.
